UNITED STATES PATENT OFFICE.

CHARLES A. HIDER, OF BALDWIN, INDIANA.

MOTOR-VEHICLE.

SPECIFICATION forming part of Letters Patent No. 732,553, dated June 30, 1903.

Application filed April 23, 1903. Serial No. 153,893. (No model.)

To all whom it may concern:

Be it known that I, CHARLES A. HIDER, a citizen of the United States, residing at Baldwin, in the county of Allen, in the State of Indiana, have invented certain new and useful Improvements in Motor-Vehicles; and I do hereby declare that the following is a full, clear, and exact description of the invention, which will enable others skilled in the art to 5 know which it appertains to make and use the same, reference being had to the accompanying drawings, which form part of this specification.

My invention relates to improvements in 15 motor-vehicles.

The primary object of my present invention is to provide a motor-vehicle having improved driving and steering mechanisms so constructed and arranged that the axles can 20 be readily and conveniently shifted in turning without interfering in the least with the driving connection of the sprocket-chains with the driving-axles.

The principal novel feature of my invention resides in the means whereby the driving connection can be uniformly maintained in the same plane during all the various shifting movements of the driving-axles incident to ordinary service, thereby obviating all danger of derangement thereof.

My invention consists of a vehicle-body or skeleton frame pivotally mounted upon carrying-axles and supporting-wheels, an improved driving mechanism connecting the 35 axles with a centrally-arranged power-transmitting shaft, an improved friction power-transmitting gearing, and an improved steering mechanism.

In the accompanying drawings, in which 40 similar reference-numerals indicate like parts throughout the several views, Figure 1 is a plan view of my invention with the frame and friction-disk broken away in part, and the bolsters, standards, and fifth-wheels are 45 omitted, showing the relative arrangement of the driving and steering mechanisms with the supporting-wheels and axles shown in a shifted position for turning. Fig. 2 is a longitudinal vertical section on the line Z Z of 50 Fig. 1. Fig. 3 is a cross-section taken on the line X X of Fig. 2 looking toward the forward end of the vehicle and showing the rel-

ative arrangement of the power-transmitting shaft and the friction-gear and also showing a portion of the axle-shifting mechanism. 55 Fig. 4 is an enlarged detail side view of the improved means for avoiding displacement of the driving mechanism and consisting of a rigidly-supported sheath or casing, a sprocket-ring, a knuckle-ring, and a hub 60 keyed on the axle. Fig. 5 is a cross-section of Fig. 4, taken on the line y y of Fig. 4, showing the manner of mounting the sprocket-ring in its sheath or casing.

Referring now particularly to Figs. 1 and 65 2, the vehicle body or frame 1, of any proper form, size, or material, is pivotally mounted upon the forward and rear bolsters 2 and 3, the fifth-wheels 4 and 5, and the spring-platforms 6 and 7 united, as usual, by a proper king-bolt 12 and which in turn are supported upon driving-axles 8 and 9 and the ground-wheels 10 and 11, all of any proper construction and arrangement. The frame 1 has a transverse plate 13 on its forward end in which 75 the upright steering-shaft 14 is revolvably mounted. The upper end of this shaft is shown broken away; but it may be provided with any suitable hand-lever for operating the same. The frame 1 has a second transverse plate 15 at or near the middle of its length in which the upper end of the vertical power-transmitting shaft 23 forms a bearing and is provided with a pair of pendent hanger-brackets 16 and 17, in which is rotatably 85 mounted the transverse counter-shaft 18, Fig. 3, on which are rigidly fixed the sprocket-wheels 19 and 20 and on which is keyed the laterally-adjustable friction-wheel 21, adapted for an actuating engagement with the adjacent overhanging friction-disk 22, fixed upon the lower end of the shaft 23, which is rotatably mounted in the bracket 24, has a belt-pulley 25 fixed thereon near its upper end, and is provided with a compression-spring 26, 90 by means of which the disk 22 is normally held out of its engagement with the wheel 21. In the lower end of the brackets 16 and 17 is rigidly fixed a transverse box 27, provided upon its lower face with the longitudinal 100 guiding-slot 28 for the pendent pivot 29, fixed in the lower face of the block 30, slidably mounted in the box 27 and to whose ends the rear ends of the shifting ropes or cables 31

and 32 are secured. These ropes pass over the idlers 33, 34, 35, 36, 37, and 38, respectively, on the brackets 16 and 17 and the frame 1 and have their forward ends so secured to the pulley 39 on the shaft 14 as to be adapted to wind thereon in opposite directions in a well-understood manner. The axles are provided with hounds 8' and 9', having upon their inner ends the respective plates 40 and 41, having a central opening in which the pins 42 and 43 are respectively loosely mounted and have their inner ends pivotally mounted on the pendent pin 29, fixed in the block 30, as before described. This construction permits a convenient shifting of the axles and hounds, as shown in dotted outline in Fig. 1, by the manipulation of the steering-shaft 14, by means of which the block 30 is shifted longitudinally in the box 27 by means of the ropes 31 and 32. At a suitable point on the axles 8 and 9, approximately midway of their ends, are arranged the sprocket driving-wheels 44 and 45, respectively, identical in construction and firmly supported in position by means of the respective stay-rods 46 and 47, Fig. 1, whose inner ends are fixed to the inner face of the brackets 16 and 17.

The shaft-driving sprocket-wheels above mentioned are constructed as follows, referring particularly to Figs. 4 and 5: In a two-part casing formed of two rings 48, rigidly united by means of bolts 49 through opposite radial lugs 50, is rotatably mounted a sprocket-ring 51, whose teeth project through an annular peripheral slot and is provided upon each side with an annular flange 52. These flanges fit loosely in corresponding annular recesses in the adjacent faces of the casing or sheath, Fig. 5. Within the sprocket-ring 51 and in concentric relation therewith is arranged a second ring 53, which might be termed a "knuckle-ring" and is provided upon two diametrically opposite points of its perimeter with the fixed radial arms 54, whose free ends are loosely mounted in suitable sockets or openings in the inner face of the ring 51. The knuckle-ring is supported in concentric relation to its axle-shaft by means of the rigidly-fixed hub 55, keyed thereto in the usual manner and provided with the rigid diametric radial arms 56, whose outer ends are loosely mounted in suitable sockets in the inner face of the ring 53, which sockets are arranged at right angles to the radial arms 54. By this construction I secure a simple, reliable, and efficient knuckle-joint in the sprocket-wheel which permits a free shifting movement of the said axles and hounds without the least derangement of the driving-sprockets, as the ring 51 will maintain the same plane relative to its actuating-sprocket on the shaft 18.

In the guide-lugs 57 and 58, which are fixed on the rigid cross-piece 59 on the lower face of the frame 1, is slidably mounted the transverse rod 60, provided with a fixed rearwardly-projecting lever-arm 61, whose free end normally engages a peripheral recess on the fric-

tion-wheel 21, whereby it is adapted to shift this wheel laterally upon the counter-shaft 18 when it is desired to reverse the motion of the vehicle in a well-understood manner.

The sprocket-wheels 19 and 20 on the driving-shaft 18 are operatively connected to the respective sprocket-wheels 45 and 44 by means of the sprocket-chains 62 and 63, respectively.

The operation of my invention thus described is obvious and briefly stated is as follows: The belt-pulley is connected to any suitable motor, which can be mounted in any proper part of the vehicle, thereby imparting rotation to the shaft 23 and the friction-disk 22, which is held normally out of engagement with the perimeter of the friction-wheel 21 by the coil-spring 26, but is adapted to be brought into such engagement by a proper pressure upon the upper end of the shaft 23 by any suitable means, thereby imparting rotation to the same and to the shaft 18, on which it is slidably keyed. The rotation of the shaft 18 actuates the axles 8 and 9 through the driving connection formed by the sprocket-wheels 19, 20, 44, and 45 and the sprocket-chains 62 and 63.

The vehicle can readily be steered at pleasure by means of the steering-shaft 14, the ropes 31 and 32, and the slidable block 30, as heretofore described.

When it is desired to reverse the motion of the vehicle, the operator shifts the friction-wheel laterally to a position on the opposite side of the center of the friction-wheel from that shown in Fig. 3 by means of the lever 61.

Having thus described my invention and the manner of operating the same, what I desire to secure by Letters Patent is—

1. In a motor-vehicle a driving-gear consisting of a transverse counter-shaft; a pair of sprocket-wheels fixed on the said shaft; a friction-wheel adjustably mounted on the shaft; means for transmitting power to the friction-wheel; a pair of sprocket-wheels fixed on the carrying-axles by a knuckle-joint connection as described; and a pair of sprocket-chains operatively connecting the sprocket-wheels on the counter-shaft with the sprocket-wheels on the axles.

2. In a motor-vehicle a driving mechanism consisting of a counter-shaft; sprocket-wheels fixed on the counter-shaft; a friction-wheel slidably mounted on the said shaft; an actuating friction-disk rotatively mounted in co-operative relation with the friction-wheel; means for actuating the friction-disk; sprocket-wheels fixed on the carrying-axles by a knuckle-joint connection for the purpose specified; and a sprocket-chain driving connection between the counter-shaft sprocket-wheels and the axle sprocket-wheels.

3. In a driving-gear for motor-vehicles a sprocket-wheel adapted for a knuckle-joint connection with its shaft, and consisting of a sprocket-ring rotatably mounted in a two-part sheath; a concentric hub having a pair of op-

posite radial arms; and an interposed concentric ring loosely engaged by the said hub-arms, and provided with a pair of opposite radial arms adapted for a pivotal engagement with the sprocket-ring at right angles to its engagement with the hub, all substantially as described.

4. In a motor-vehicle driving-gear a sprocket-wheel adapted for a knuckle-joint connection with its shaft, and consisting of a hub having a pair of fixed radial arms in opposite relation; a concentric intermediate ring pivotally mounted on the hub-arms and provided with a pair of opposite radial arms in right-
15 angular relation to the hub-arms; and a sprocket-ring loosely mounted on the arms of the said intermediate ring; and a supporting sheath or case having a peripheral annular slot through which the teeth of the sprocket-
20 ring project, all substantially as described.

5. In a motor-vehicle gearing a power-transmitting mechanism consisting of a friction-wheel slidably mounted on a counter-shaft; means for shifting the friction-wheel; a vertical shaft rotatably mounted in suitable bearings having a belt-pulley for connection with the motive power, and provided upon its lower

end with a fixed friction-disk adapted for an actuating engagement with the friction-wheel, and provided with a coiled compression-spring adapted to normally secure the said disk out of such engagement.

6. In a motor-vehicle the combination of a counter-shaft; a pair of sprocket-wheels fixed on the shaft; a friction-wheel slidably keyed on the shaft; means for actuating the said wheel; a pair of sprocket-wheels fixed on the carrying-axles by a knuckle-joint connection; a sprocket-chain connection between the counter-shaft and axle sprocket-wheels; and a pivotal connection between the axles formed by a pair of hounds having upon their inner ends slotted plates or blocks, and a pair of horizontal pins loosely mounted in the slots of said plates, and having their inner ends pivotally united to a sliding block; and a sliding block pivotally uniting the steering mechanism with the said hounds as described.

Signed by me at Fort Wayne, Allen county, State of Indiana, this 10th day of April, 1903.

CHARLES A. HIDER.
